UNITED STATES PATENT OFFICE.

HARRY LEMISZCZAK, OF YONKERS, NEW YORK.

ANTISUBMARINE DEVICE.

1,294,920.

Specification of Letters Patent. Patented Feb. 18, 1919.

Application filed August 6, 1917. Serial No. 184,691.

To all whom it may concern:

Be it known that I, HARRY LEMISZCZAK, a subject of the Emperor of Austria, resident of Yonkers, county of Westchester, and 5 State of New York, have invented certain new and useful Improvements in Autisubmarine Devices, of which the following is a specification.

This invention relates to improvements 10 in protecting devices for the hulls of vessels, and has as its special object the provision of means which may rapidly be suspended from the hull of a vessel and arranged to form an effective guard against torpedoes 15 and the like, which are prevented from causing damage to the vessel.

This object is attained by the novel construction and combination of parts hereafter described and shown in the accompanying drawings, forming a material part 20 of this disclosure, and in which—

Figure 1 is a side elevational view of a conventional type of vessel indicating the application of the invention.

Fig. 2 is a fragmental view of one of the 25 deflecting plates, the view being taken substantially on line 2—2 of Fig. 3.

Fig. 3 is a transverse vertical sectional view taken on line 3—3 of Fig. 1.

Fig. 4 is a top plan view illustrating the 30 application of guard plates to a vessel.

Fig. 5 is a fragmental vertical sectional view similar to Fig. 3, but showing a modification in construction.

Fig. 6 is a sectional view of the same 35 taken on line 6—6 of Fig. 5.

Fig. 7 is a fragmental side elevational view of the same.

Fig. 8 is a transverse vertical view taken 40 on line 8—8 of Fig. 7, and

Fig. 9 is a perspective view looking from 45 the inner side of one of the guard plates.

As it is obvious that an armor plate disposed at a distance from the walls of the 50 vessel, will impede its movement through the water, it is desirable to provide such armor plates in forms which may be readily attached to the gunwales of a vessel in a time of need, and which may normally be carried upon the vessel itself.

The present invention comprises a plurality of substantially rectangular armor plates 10, adapted to be suspended by straps 11, the same being hooked-shaped and 55 adapted to engage over the top edge of the vessel so as to hang pendently beside the

hull 13, and in order to provide a desirable degree of resilience to the plate 10, a plurality of arcuate or elliptical springs 15 are attached by rivets 16 to the plate upon one 60 side, the springs being disposed one above the other in a vertical row in such manner that the opposite side of the spring will make contact with the vessel hull 13, so that if the plate 10 receives the shock or impact 65 of a projectile, a certain amount of resilience is obtainable, tending to cushion the blow transmitted to the walls of the vessel, and it will be obvious that the armor plates are substantially straight along the sides 70 and bent in conformity with the outline of the vessel at the stern and bow thereof.

In place of the elliptical spring 15 it may be preferred to use the device shown in Figs. 75 5 and 6, in which a plurality of resilient contact elements 20 are firmly engaged to the plates 18 the edges 21 and 22 of the plate being beveled and arranged in vertical rows in the manner of the scales of a fish, the edge of one slightly overlapping that of the succeeding plate.

In order to hold these plates in relation with the sides 13 of the vessel, a plurality of bolts 23, are affixed in the walls of the vessel, the same extending through the 80 plates 18 and secured in position by means of the nuts 24, there being disposed between the walls 13 of the vessel and the plates 18, spirally coiled compression springs 25, the same circling the shanks of the bolts 23. 90

In this form, each of the plates is independently suspended and so held as to be able to move in toward the vessel until the springs and resilient elements have absorbed the shock or blow. 95

In Figs. 7 to 9 inclusive a somewhat similar arrangement of sectional plates is indicated, each of the plates 30 having beveled edges and a central opening 32, receptive of the reduced stem 35, of posts 36, supported 100 by brackets 37, secured by screws 38 or the like to the wall 13 of the vessel, the posts having shoulders against which the inner side of the guard or armor plates make contact and which are held in position by 105 means of the nuts 40, all of these several guard or armor plates being formed with rigid projections 42 at their corners, the inner rounded points of which make contact with the vessel hull, presenting in effect 110 a substantial, rigid outer casing for the vessel.

From the foregoing it will be seen that a substantial arrangement for protecting the hulls of vessels has been disclosed.

Having thus described my invention what 5 I claim as new and desire to secure by Letters Patent, is:—

In a ship's armor of the character described, the combination of a plurality of centrally perforated plates having beveled 0 edges, with posts adapted to space and hold said plates apart from the ship's hull, reduced stems on said posts passing through the perforations of said plates, brackets on

the opposite ends of said posts for securing the same to the ship's hull, nuts for holding 15 said plates in engagement with the shoulders of said posts formed by said reduced stems, and frusto-conical projections at the corners of said plates adapted to engage with their free ends the ship's hull, substantially as described and for the purpose set forth.

In testimony whereof I have affixed my signature.

HARRY LEMISZCZAK.
